UNITED STATES PATENT OFFICE.

ROSCOE ROYAL, OF CHICAGO, ILLINOIS, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed July 24, 1926. Serial No. 124,643.

This invention relates to electro-magnetic devices, and more particularly to electro-magnetic relays of the type used in telephone systems.

5 The object of the invention is to provide a relay of simple, compact parts which may be readily and quickly assembled.

In accordance with the object, the invention contemplates the provision of an elec-10 tro-magnetic structure adapted when traversed by an electric current to actuate an armature which is pivotally supported by a member which also acts as a stop to determine the distance of travel of the armature.

15 It is believed that the invention will be clearly understood from the following detailed description taken in connection with the accompanying drawing, in which

Fig. 1 is a side elevation of an electro-20 magnetic device embodying the invention;

Fig. 2 is a detail view of the armature forming a part thereof;

Fig. 3 is a plan view of the underside of the device as viewed in Fig. 1;

25 Fig. 4 is an end view thereof;

Fig. 5 is an enlarged fragmentary sectional view taken substantially on line 5-5 of Fig. 4, and

30 Fig. 6 is a detail view of the combined hinge and stop member forming a part thereof.

In the drawing, in which like numerals designate similar parts throughout the several views, the numeral 10 designates a flat core made of magnetic material such as iron, which is provided at its ends with enlarged portions 11 and 12 adjacent which are mounted insulating plates 13 and 14. A coil 15 composed of a plurality of turns of a fine

40 insulated wire is wound upon the core 10 between the insulating plates 13 and 14 and the ends of the wire forming the coil 15 are connected to terminals 16 and 17 secured to the lower side of the enlarged end 11 in a manner hereinafter described. The enlarged end 11 is provided with offset lugs 19 and 20 in which are threaded holes to receive screws for securing the device to a mounting plate. The enlarged end 11 is provided 45 with holes through which screws 23-23 and 24-24 are inserted for assembling the device.

On the lower side of the enlarged end 11 in addition to the terminals 16 and 17 there

are mounted resilient members 26, 27, 28 and 29, insulated from each other, from the terminals 16 and 17 and from the enlarged end 11 by a plurality of small insulating plates 30. The assembly screws 24-24 pass through the insulating plates 30, the resilient members 26 and 27, the terminal 16, the enlarged end 11, the terminal 17 and the resilient members 28 and 29 and are threaded into a small plate 31, the plate 31 and the screws 24 cooperating to grip the above 55 mentioned members tightly together. The resilient member 26 is provided at one end with a terminal portion 33 similar to the terminals 16 and 17 and at the other end is provided with a small contact plate 35. The 60 resilient member 27 is provided at one end with the terminal portion 34 and at the other end with a contact point 36 designed to cooperate with the contact plate 35 carried by the resilient member 26. The resilient members 26 and 27 are disposed so as to normally spring apart and maintain the contact members 35 and 36 separate.

The resilient members 28 and 29 are provided with terminal portions 38 and 39 at 65 one end and with contact members 40 and 41 near the other end similar to those described for the resilient members 26 and 27. The resilient member 29 is constructed at the end opposite the terminal end in the form of a 70 U, one leg of which is adjacent the resilient member 27 and is provided with an insulating block 42 which is maintained in contact with the member 27 by the resilience of the member 29 so as to force the contact point 36 carried by the member 27 into engagement with the contact plate 35 carried by the member 26.

A bar 44 is secured to the enlarged end 11 of the core 10 by means of the assembly screws 23-23 in a position substantially 75 parallel to the core 10 and upon the end of the bar 44 adjacent the enlarged end 12 of the core 10 is mounted an armature 45 by means of a combined hinge and stop member 46. The armature 45, composed of a magnetic material, is provided at its upper end with lugs 47-47 and at the opposite end with an offset arm portion 48 upon which is mounted an insulating block 49. The combined hinge and stop member 46 80 comprises a bow shaped strip of a resilient 85 non-magnetic material which is designed to 90

be sprung over the bar 44 and the enlarged end 12 of the core 10 in the position shown in Fig. 4. One end of the member 46 is bent to partially encircle the bar 44 and this end is slotted to receive the upper end of the armature 45 leaving prongs 50-50 which are bent to form circular beads which surround the lugs 47-47 on the armature 45 and act as hinge members in which the lugs 10 47-47 of the armature 45 may rotate. A portion is cut out of the end of the member 46 adjacent the enlarged end 12 of the core 10 through which the offset end 48 of the armature 45 is inserted, and a partially severed portion 51 is pressed out from the member 46 to act as a stop to regulate the distance of travel of the armature 45. In its assembled position the armature 45 is normally restrained in contact with the stop 20 portion 51 by the resilience of the member 28 acting against the insulating block 49 carried by the armature 45.

In operation conductors from a controlled electric circuit may be connected to the terminals 33 and 34, conductors from a controlling circuit may be connected to the terminals 16 and 17 and conductors from another controlled circuit may be connected to the terminals 38 and 39. The contact 25 members 35 and 36 carried by the members 26 and 27 will be maintained in contact by the insulating block 42 being forced against the resilient member 27 by the resilience of the member 29, and the armature 45 will be 30 retained against the stop member 51 by the resilience of the member 28 acting against the insulating block 49 carried by the armature 45, the resilience of the member 28 also maintaining the contact members 40 and 41 carried by the members 28 and 29 separated.

When it is desired to actuate the relay and effect a change in the controlled circuits, the circuit connected to the terminals 16 and 45 17 which includes a source of electrical energy is closed causing a current to flow through the coil 15, thereby magnetizing the core 10. When the magnetic force in the core 10 becomes sufficient to overcome the resilience of the member 28, the armature 45 is drawn into contact with the enlarged end 12 of the core 10. The offset end portion of the armature 45 then moves the resilient member 28 in the direction of the member 29 until the contact member 40 carried by the member 28 comes into contact with the contact plate 41, thereby closing the circuit connected to the terminals 38 and 39. The resilient member 29 is also forced 60 aside carrying with it the U-shaped end portion, thereby releasing the pressure of the insulating block 42 carried thereby from the member 27 which allows the contact members 35 and 36 to separate due to the 65 resilience of the member 27, and the circuit

connected to the terminals 33 and 34 is opened.

When it is desired to place the controlled circuits in their original condition, the circuit connected to the terminals 16 and 17 is 70 opened. The current then ceases to flow in the coil 15, the core 10 is demagnetized, and the armature is forced into its original position against the stop 51 by the resilient member 28. The circuit connected to the terminals 38 and 39 is then broken by the movement of the resilient member 28 away from the member 29, while the circuit connected to the terminals 33 and 34 is closed by the resilient member 29 acting through 80 the insulating block 42 against the resilient member 27 to cause the contact 36 carried by the latter member to engage the contact plate carried by the member 26.

The members 26, 27, 28 and 29 may be 85 made of any desired resiliency so that the magnetic force necessary to actuate the armature may be made large or small, while the pressed out stop member 51 may be bent with a suitable tool either toward or away from the armature 45 to vary the distance of travel of the armature. The number of turns of wire in the coil 15 may also be varied as desired to regulate the amount of 90 magnetic force set up in the core 10.

It is to be understood, of course, that the apparatus disclosed in the above description is illustrative only and that various changes in the size and arrangement of parts may be made within the scope of the appended 100 claims. The connection of the circuits as described above is only one of many combinations and various circuits may be used without departing from the scope of the invention.

What is claimed is:

1. In an electro-magnetic device, an armature, means responsive to an electric current for actuating the armature, a support, and a stationary member for pivotally securing said armature to the support and having a portion to limit the movement of the armature.

2. In an electro-magnetic device, an armature provided at one end with laterally extending lugs, means responsive to an electric current for actuating the armature, a support, and a member composed of a non-magnetic material engaging the lugs of said armature for pivotally securing it to the support and having a portion for limiting the movement of the armature.

3. In an electro-magnetic device, an armature provided at one end with laterally extending lugs, means responsive to an electric current for actuating the armature, a support, and an integral, non-magnetic hinge and stop member provided at one end with means for encircling the lugs on the armature to pivotally secure the armature to the

support and having a cut-out portion through which the armature is inserted, leaving a partially severed struck-out portion for limiting the movement of the armature.

4. In an electro-magnetic device, an armature, means responsive to an electric current for actuating the armature, a support, a combined hinge and stop member composed of a resilient, non-magnetic material designed to be sprung over the end of the support to pivotally secure the armature to the support and to limit the movement of the armature, and resilient means for nor-

mally maintaining the armature against the stop member.

5. In an electro-magnetic device, an armature, means responsive to an electric current for actuating the armature, a support, and means separable from said armature for pivotally securing it to the support and having a portion cooperating with the free end of the armature for determining its unattracted position.

In witness whereof, I hereunto subscribe my name this 10th day of July A. D., 1926.

ROSCOE ROYAL.
